UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS DOING BUSINESS
AS BARBER-COLMAN COMPANY, OF ROCKFORD, ILLINOIS.

CREEL.

1,275,850.

Specification of Letters Patent.

Patented Aug. 13, 1918.

Application filed July 30, 1913. Serial No. 781,919.

To all whom it may concern:

Be it known that I, HOWARD D. COLMAN, a citizen of the United States, residing at Rockford, in the county of Winnebago and 5 State of Illinois, have invented certain new and useful Improvements in Creels, of which the following is a specification.

This invention relates to creels such, for example, as are used to support the spools, 10 cheeses or other yarn masses which are to be unwound in forming a warp. The invention has particular reference to the type of creel comprising removable sections adapted to be used at the spooler or winder as a receptacle or support for the yarn masses when removed from the spooler or winder and adapted to be transported to and placed in the creel.

In the accompanying drawings, Figure 1 20 is a side elevation of a warper creel embodying the features of my invention, the creel being shown in operative relation to a warper. Fig. 2 is an elevation of a thread-guiding structure located between the creel 25 and the warper, the view being taken in the plane of dotted line 2 of Fig. 1. Figs. 3 and 4 are fragmental details of certain yarn-guiding devices. Fig. 5 is an end view of the creel, the view being taken in the plane 30 of dotted line 5 of Fig. 1. Fig. 6 is a plan view of one of the removable creel-sections loaded with cheeses. Fig. 7 is a sectional view of one of the creel-sections, the view being taken in the plane of dotted line 7 of 35 Fig. 6. Fig. 8 is a view illustrating the manner in which the yarn masses are mounted for rotation on the creel-sections.

The present embodiment of the invention is especially adapted for cylindrical yarn 40 masses wound upon cores *a*, such yarn masses being termed cheeses, but it will be understood that the invention is susceptible of use in connection with yarn masses of various other forms.

In the form herein shown, the creel 45 consists of a stationary supporting structure or frame 1 and a plurality of removable cheese-supporting sections 2. In this instance, the supporting framework is adapted to support six horizontal rows or series of creel-sections 50 2, there being three such rows on each side of the creel frame. As herein shown, the frame 1 comprises pairs of cross-bars 3 which are rigidly secured to upright frame-

members 4, said frame-members being secured together by means of longitudinal bars 5. At one side of the creel frame are longitudinal bars 6 secured to the ends of the bars 3. On the opposite side of the creel frame is a bar 7 connected to the ends of the lowermost pairs of cross-bars 3. The parts 3, 5 and 6 constitute shelf-like structures upon which a plurality of horizontal series of creel-elements may be removably supported.

Each of the removable creel-sections 2 comprises an elongated base 8 carrying a suitable number of cheese supports. Herein each base is shown as provided with three sets of cheese-supporting elements, each set 70 consisting of a spindle 9 (Fig. 7) rigidly secured to the base and rotatably supporting a suitable number of rollers 10 on which the cheeses may be mounted. Herein I have shown four such rollers on each spindle. At 75 the outer end of the spindle is fixed a sleeve or tip 11. 12 are suitable washers.

As shown in Fig. 8, the ends of the rollers 10 are reduced in diameter, thus forming an annular shoulders 13 preferably of conical or 80 tapering form adapted to lie between the internal shoulders *b* of the cheese cores *a*, whereby the cheeses are prevented from moving laterally into contact with adjacent cheeses when revolving in the creel. The greatest diameter of the roller 10 is sufficiently 85 less than the smallest internal diameter of the cheese core, so that the cheese core may be readily slipped on and off the roller by the operative. When the creel section is in 90 place on the creel frame, the cheese cores *a* are out of contact with each other. When the creel section is in a vertical position, the cheese cores on a given spindle rest upon one another.

The creel-sections 2 are adapted to be supported upon their sides upon the cross-bars 3 of the creel frame, the tips of the spindles resting upon the bars 5 and 6, and the creel-sections being held against displacement longitudinally of the cross-bars by reason of the fact that the bases 8 lie in shallow recesses 14 in the cross-bars.

The means for guiding the yarn from the cheeses to the warper *W* (which machine may 105 be of any suitable character) comprises a rigid frame 15 secured in upright position between one end of the creel and the warper.

In the frame 15 are secured devices for guiding the individual strands. In the form herein shown, these devices are formed by means of bars 16 having eyes 17 therein. 5 There is one such bar for each row of cheeses extending longitudinally of the creel. In this instance the eyes 17 are provided by forming each bar 16 of two thin bars 16^a welded or otherwise secured together, in each 10 of which bars is a series of bayonet slots, the slots of the two bars extending in opposite directions, and the points 17^a formed by the cutting of said slots being bent outwardly, as indicated in Fig. 4 so as to provide an inclined entrance to each eye. The thread may be readily inserted into the eye by the operative, but can not leave said eye 15 in the operation of the warper.

The frame 15 is secured in place by any 20 suitable means as, for example, braces 18 extending between said frame and the creel frame.

The cheeses are not intended to be wholly 25 unwound. After the desired amount of yarn has been unwound from the cheeses, the strands are severed, and the creel-sections 2, with the cheese cores remaining thereon, are lifted from the creel frame and transported to the winder. They are there 30 positioned or handled in such a way that it shall be convenient for the winder operatives to take the cheese cores off the spindles 9 and place them on the winder, full cheeses 35 when removed from the winder being immediately placed on the spindles 9. When the creel-sections are full, they are returned to the warper room to be again placed upon the creel frame, the ends of the yarn on the cheeses being tied or otherwise connected to 40 the old threads.

The invention is claimed generically in application Serial No. 133,982, filed Nov. 28, 1916.

I claim as my invention:

45 1. A creel having, in combination, a frame comprising a plurality of horizontal superposed shelf-like structures, a series of creel sections removably supported upon each shelf-like structure, each creel section comprising a base and a plurality of horizontal 50 spindles extending at right angles to the base, said bases extending longitudinally of the shelf-like structures, the spindles extending horizontally and transversely of the shelf-like structures, each spindle being of sufficient length to support a plurality of yarn carriers, the running threads of the 55 yarn carriers extending longitudinally of and between the shelf-like structures, and means at one end of the frame for guiding the running threads.

60 2. A creel having, in combination, a frame comprising a plurality of horizontal superposed shelf-like structures, and a series of 65 creel sections removably supported upon

each shelf-like structure, each creel section comprising a base and a plurality of horizontal spindles extending at right angles to the base, said bases extending longitudinally of the shelf-like structures and the spindles 70 extending horizontally and transversely of the shelf-like structures, the running threads of the yarn carriers extending longitudinally of and between the shelf-like structures.

3. A creel having, in combination, a shelf-like structure, a series of creel sections removably supported upon said structure, each creel section comprising a base and a plurality of horizontal spindles extending at right angles to the base, said bases extending 80 longitudinally of the shelf-like structure and the spindles extending horizontally and transversely of the shelf-like structure, each spindle being of sufficient length to support a plurality of yarn carriers, the running 85 threads of the yarn carriers extending longitudinally of and above the shelf-like structure.

4. A creel consisting of a frame comprising a horizontal row of supports and horizontal supporting means extending parallel with and in approximately the same horizontal plane as said row of supports, and creel sections removably supported by said row of supports and said horizontal supporting means, and comprising yarn-mass-supporting spindles extending transversely of said row of supports.

5. A creel comprising a frame, a plurality of superposed horizontal rows of creel sections removably supported on said frame, 100 said rows being spaced apart to provide passageways for the threads between the rows, and yarn-guiding means located at one end of said rows and in line with said passageways.

6. A creel having, in combination, a creel section consisting of an elongated base and a plurality of spindles, a horizontal support having a socket to receive one longitudinal 110 edge of said base, and means to support the tips of the spindles.

7. A creel having, in combination, a plurality of horizontal superposed series of spindles, said spindles extending transversely of the series, and each spindle being of sufficient length to support a plurality of yarn carriers, said spindles extending horizontally, and the running threads of the 115 yarn carriers which are mounted upon the lower horizontal series of spindles extending longitudinally of and between the series of spindles.

8. A creel having, in combination, a frame comprising a plurality of horizontal superposed shelf-like structures, a series of creel sections removably supported upon each shelf-like structure, said series extending longitudinally of the shelf-like structures, each creel section comprising a base and a 125

plurality of horizontal spindles, said spindles extending transversely of the series of creel sections, and each spindle being of sufficient length to support a plurality of 5 yarn carriers, the running threads of the yarn carriers extending longitudinally of and between the shelf-like structures.

In testimony whereof I affix my signature in presence of two witnesses.

HOWARD D. COLMAN.
